[57] ABSTRACT

Upper and lower advancing means advance tubular stock in downward direction and in a predetermined path which comprises at least some superimposed helical convolutions of low pitch. A feed device is arranged at the upper end of the path and a takeup device is arranged at the lower end of the path for the tubular stock. Extruding means is arranged adjacent one of the convolutions for extruding onto the outer circumferential surface of the advancing tubular stock a circumferentially complete jacket of cellular synthetic plastic. Forming means is arranged adjacent a second convolution downstream of the extruding means forming the peripheral surface layer of the obtained jacket into a continuous smooth skin. Cooling means is arranged adjacent still a further convolution downstream of the forming means and cools the resulting jacketed tubular product.

APPARATUS FOR JACKETING TUBULAR STOCK

CROSS-REFERENCE TO COPENDING APPLICATIONS

A copending application was filed on Sept. 20, 1968 in the name of Helmut Benteler et al.; it has Ser. No. 761,221 and is entitled "Method of and Apparatus for Jacketing Tubular Stock."

BACKGROUND OF THE INVENTION

The present invention relates generally to the jacketing of tubular stocks, and more particularly to the jacketing of bendable tubular stock with synthetic plastic material.

From the aforementioned copending application it is already known to continuously jacket a tubular stock with a thermally and acoustically insulating cover of cellular synthetic plastic. The cold or cool tubular metallic stock is passed through the extrusion die of an extruder and jacketed with a mixture of preplasticized foamable synthetic plastic material and between 0.2 and 1.5 parts by weight of foaming agent. The gases which develop and/or air are simultaneously withdrawn from the region of initial contact between the synthetic plastic and the metallic stock. Subsequently the outer peripheral surface of the thus-produced jacket of foamed synthetic plastic is smooth and the thus-obtained jacketed tubular product is cooled.

According to this previous application the mixture of plastic, preferably but not necessarily polyolefin, and foaming agent which is preferably but not necessarily azodicarbonamide, is preplasticized by heating to between approximately 180° and 225° C. and being subjected to feed-screw pressure on the order of approximately 130 atmospheres. It is thereupon applied to the tubular stock. The cooling follows the smoothing of the peripheral surface of the jacket, and the smoothing is carried out under the influence of elevated temperatures. The cooling takes place in a series of graduated cooling stages.

The method and apparatus disclosed in the aforementioned copending application is concerned with the jacketing of tubular stock which is advanced in a straight or substantially straight path which is completely or substantially completely horizontal. However, there are circumstances where it is necessary or desirable that the path traversed by the tubular stock being jacketed is vertical or near vertical. On the other hand, the path must not be excessively long in these circumstances because this would require very high installations, making access difficult, requiring large amounts of space, and presenting other problems.

The invention disclosed in the aforementioned copending application cannot be used for this purpose. It is, however, desirable to provide an apparatus which is capable of affording the jacketing of tubular stock in the manner disclosed in the aforementioned copending application, but with the stock traveling in upright or near upright path.

SUMMARY OF THE INVENTION

It is, accordingly, an object of the present invention to provide an apparatus affording the aforementioned advantages.

More particularly it is an object of the present invention to provide an apparatus for jacketing—preferably continuously—a relatively small-diameter tubular metallic stock advancing in a vertical or near vertical path, with synthetic foam material.

A further object of the invention is to provide such an apparatus which permits the jacketing of such stock which is supplied and taken up in form of coils rotating about their respective axes, with the upper and lower coil being spaced by only a relatively small vertical distance from one another and with the material of this relatively small diameter tubular stock being subjected to as little as possible of stretching and deformation.

In pursuance of these objects, and others which will become apparent hereafter, one feature of the invention resides in an apparatus for continuous jacketing of metallic tubular stock

with cellular synthetic plastic. This apparatus comprises, briefly stated, advancing means for advancing tubular stock in downward direction and in a predetermined path which comprises at least some superimposed helical convolutions of low pitch. Feed means and takeup means are provided for the tubular stock and are respectively arranged upstream and downstream of the advancing means. Extruding means is arranged adjacent a first one of the convolutions for extruding onto the outer circumferential surface of the advancing tubular stock a circumferentially complete jacket of cellular synthetic plastic. Forming means is adjacent a second convolution downstream of the first convolution for forming the peripheral surface layer of the thus-obtained jacket into a continuous smooth skin. Finally, cooling means is adjacent a third convolution downstream of the second convolution and serves for cooling the resulting jacketed tubular product.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWING

FIG. 1 is a diagrammatic side elevational view of an apparatus according to the present invention;

FIG. 2 is a horizontal longitudinal section through an extrusion head for use in the apparatus of FIG. 1;

FIG. 3 is a view similar to FIG. 2 but illustrating a further extrusion head;

FIG. 4 is a longitudinal section through a forming and smoothing device for use in the apparatus of FIG. 1;

FIG. 5 is a transverse section of the device shown in FIG. 4;

FIG. 6 is a longitudinal section through a floating support for the jacketed tubular product, for use in the apparatus of FIG. 1;

FIG. 7 is a transverse section of the support shown in FIG. 6; and

FIG. 8 illustrates how opposite end portions of successive lengths of a jacketed tubular product can be connected with one another.

DESCRIPTION OF THE PREFERRED EMBODIMENTS

Discussing now the drawing in detail, and firstly FIG. 1, it will be seen that we have illustrated an apparatus for the continuous jacketed of metallic tubular stock of relatively small diameter. This apparatus comprises an upper payoff device utilizing a payoff drum 2 and a lower device for takeup utilizing a takeup drum 2a. Both of the drums rotate in horizontal planes about upright axis of rotation and in the illustrated embodiment the axes of both drums 2 and 2a are in alignment.

In the illustrated embodiment the vertical distance between the drums 2 and 2a is only so large that the tubular stock 1—which is of metal and of relatively small diameter—passes downwardly from the upper coil 30 carried by the drum 2 and reaches the lower drum 2a after traversing only a few helical convolutions of relatively low pitch. It is taken up onto the drum 2a in form of a lower coil 30. According to the present invention it is advantageous that the diameter of the helical convolutions is at least substantially identical with the diameter of the coils 30 and 30a.

Intermediate the drums 2 and 2a and spaced from one another by a distance corresponding to somewhat more than two of the helical convolutions, are the advancing devices 3 and 3a. These define in the vertical space between themselves the path wherein the tubular stock is to be jacketed with a jacket of foamed synthetic plastic material.

The application of this jacket is accomplished by means of the extrusion die 4 of an extruder 5. It is possible to provide the extrusion die with an annular smoothing or forming means analogous or corresponding to that disclosed in the aforementioned copending application.

However, in accordance with the present invention, the die may not be provided with this device and a separate device 31 for forming and smoothing of the peripheral surface of the applied jacket may be provided. This device 31 will be described subsequently in more detail.

Downstream of the device 31 there is provided cooling means 11, 12 which is diagrammatically illustrated and in the embodiment shown defines two sections which are supplied with cooling media of different temperature. The first section is supplied with a cooling medium whose temperature is higher than that of the second section so that the jacketed tubular product is cooled in two successive stages. Once the jacket is cooled in this manner, it has its final strength so that the jacketed tubular product can then be advanced on roller supports 32 until it has passed the lower advancing device 3a and reaches the lower drum 2a of the takeup. It is advantageous that the advancing devices 3 and 3a be synchronously driven.

According to the invention it is advantageous that in the region of the cooling means 11, 12 the helical convolutions be supported by a floating support 33. Several of these supports 33 may be provided and distributed in suitable manner. The smoothing or forming device 31 itself may also fulfill the function of such a floating support or be replaced by one, that is if the extrusion die is provided with the annular type of smoothing or forming device disclosed in the copending application.

There is further provided an intermittently controlled cutting device, here illustrated as a saw 34, which advances in the direction and with the speed of the jacketed tubular product, being arranged downstream of the advancing device 3a. A signal generating device 35 and a feeler or scanning device 36 are provided which cooperate with the saw 34 and which are located upstream of the advancing device 3a. The reason for this arrangement is that it is customary—when the jacket is to be supplied continuously to the advancing tubular stock, the ends of successive coils or lengths of tubular stock 1 are connected in the manner shown in FIG. 1 by means of an internal connector 1a. The devices 35 and 36 detect the presence of such a connector 1a as it passes by them and, in dependence upon the speed of advancement of the tubular stock 1, these devices activate the saw 34 which then saws through the connector 1a intermediate the successive lengths of tubular stock 1 so that the takeup drum 2a will always accept coils of a predetermined length.

The extrusion head 4 of the extruder 5 utilized in the apparatus of FIG. 1 may be of the construction illustrated in FIGS. 2 or 3. A hollow mandrel 19 is provided in this case whose internal chamber 18 has a diameter greater than double the diameter of the tubular stock 1 which is to be jacketed. The hollow mandrel 19 is illustrated as being composed of two sections, namely the section 19a, a tapered nipple of which extends into the opening 37, and a rear section 19b which is provided with threads cooperating with complementary threads in the adjusting sleeve 38 so as to be axially adjustable therein. An annular member 39 is removably mounted intermediate the sections 19a and 19b approximately at the middle of the hollow mandrel 19, and is provided with a gliding guide 40 of sleevelike type which is offset in the manner illustrated. A similar glide guide 41 is provided in a sleeve 20 arranged at the inward side of the mandrel 19. These two guides 40 and 41 which are offset lengthwise determine the precise position and movement of direction of the metallic tubular stock 1 to be jacketed, so that the same is surrounded—on passing the outlet 37 with which the nipple of the section 19a defines an annular concentric gap—is jacketed with a jacket of preplasticized foamed synthetic plastic of a constant thickness. A guide sleeve 21 supports the mandrel 19 and is conically tapered at its circumference. This guide sleeve 21 delimits an annular chamber 23 surrounding the mandrel 19 and being in turn surrounded by the housing 24 and a member 24a. Synthetic plastic material is supplied to the chamber 23 from the extruder via the conduit 22. The conduit 15 communicating with the mandrel 19 is connected with a vacuum

pump and the annular member 39 may be provided with apertures so that the vacuum extends into the region of the extruder outlet.

In the embodiment illustrated in FIG. 2 the guide 40 is arranged eccentrically and the tubular stock to be jacketed passes through the outlet 37 with a slight curvature. By contrast, the embodiment of FIG. 3 provides for the tubular stock to be jacketed to pass precisely coaxial through the outlet opening, and an inclined guide opening 40 and longitudinal channels 42 are provided in the member 39. The end of the mandrel 19 has a larger diameter and the sleeve 20 provided with the guide 41 is eccentric. In all other respects the construction of the extrusion head in FIG. 3 corresponds to that of FIG. 2.

Coming now to the forming or smoothing device illustrated in FIGS. 4 and 5 it will be seen that it is provided with lower and upper members 43 and 44 which will hereafter be identified as lamellas. They are offset in comblike manner and it is preferable that the group of lamellas 44 are transversely adjustable. The lamellas are provided with rounded glide edges. A housing surrounds the lamellas 43 and 44 and a liquid is supplied to the housing, with the liquid being tempered and serving to support the tubular stock in the manner of a liquid float support. Of course, the liquid also acts as a glide means between the outer circumferential surface of the jacket and the pressure surfaces of the lamellas 43 and 44. A nozzle 45 may be provided at the inlet side of the device 31 for spraying liquid onto the first group of lamellas.

A specific glide or liquid support device 33 is illustrated in FIGS. 6 and 7. It will be seen that jets of liquid—such as water—are ejected with requisite high pressure towards one another so that the jacketed tubular stock 1 is maintained in floating condition between these opposed jets of liquid. Here, again, a nozzle ring 46 may be provided at the inlet side of the device 33.

In the embodiment of FIG. 1 the tubular stock to be jacketed and advancing downwardly from the upper coil 30 may move through helical convolutions having a radius of 1,000 mm. and a pitch of approximately 800 mm. per convolution—thus corresponding to a ratio of approximately 1:8—towards the extrusion head. Approximately 800 mm. downstream of the extrusion head the now jacketed tubular stock whose jacket is already cooled to a large extent passes through one of the liquid supports and moves out of the cooling device approximately after traversing an additional helical convolution. Subsequently it is advantageous that the tubular product thus produced be dried.

It will be appreciated that with the apparatus according to the present invention the tubular stock to be jacketed which remains cold or cool over at least most of its path, is initially self-supporting within limits of its inherent elasticity, thereby eliminating material distortions. Because of the arrangement of the various components of the device intermediate and with reference to the supply and takeup drums 2, 2a the installation cannot only be readily mounted, but also requires relatively little space and is easily accessible and easily observable. The various components of the apparatus which act upon the tubular stock—such as the extrusion head, the cooling means and the like—support the convolutions of the tubular stock and thus prevent undesired deformations thereof. Because of the vertical spacing of the drums 2 and 2a the portion of the path in which jacketing occurs is under constant precise control so that the jacket of synthetic plastic material issuing from the extruder head—which jacket is already self-supporting but not yet finally cured or hardened—is subjected to none or only insignificant surface tensions and forces as it passes through the forming device and the cooling device. Thus, although the tubular stock 1 is of smaller diameter and thin walled, undesired deformations and other stresses upon the material are excluded completely or almost completely while yet the desirable configuration of the tubular stock—prior to and subsequent to jacketing—in form of coils is maintained.

The floating support devices need or need not be provided, but they are highly advantageous because they do not affect the surface consistency of the jacket and the frictional resistance to movement is insignificant because the tendency to continue the helical downward movement is maintained only under the weight of the respective increment of jacketed tubular stock. It is advantageous that such a floating liquid support be located substantially at the midpoint of the cooling stages. However, the floating liquid support may be replaced intermediate the extrusion head and the cooling stages with the device illustrated in FIGS. 4 and 5 in which case the liquid not only serves to provide floating support but also acts as a glide means.

By utilizing one of the extrusion heads illustrated in FIGS. 2 and 3 it is possible to have the tubular stock issue from the outlet of the extrusion head coaxially therewith or add a small inclination. The extrusion head itself need not be changed but at the same time adequate space is provided by use of this particularly configurated hollow mandrel 19 for guidance of the curved increments of tubular stock. The sleevelike guides can be readily replaced if necessary and it is advantageous according to the invention if bores through which the tubular stock passes in the guides and in the outlet of the extruding head extend tangentially to the curved increment of tubular stock. By making the hollow mandrel 19 of two sections it is possible to readily replace either section when necessary, and the relatively large space between the sections serves at the same time for connection to a vacuum conduit.

It will be understood that each of the elements described above, or two or more together, may also find a useful application in other types of applications differing from the types described above.

While the invention has been illustrated and described as embodied in an apparatus for continuous jacketing of metallic tubular stock of cellular synthetic plastic, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

1. Apparatus for continuous jacketing of metallic tubular stock with cellular synthetic plastic, comprising advancing means for advancing tubular stock in downward direction and in a predetermined path which comprises at least some superimposed helical convolutions of low pitch; feed means for said tubular stock arranged upstream and upwardly of said advancing means for feeding said tubular stock thereto; extruding means adjacent a first one of said convolutions downwardly of said feed means for receiving the advancing tubular stock therefrom and for extruding onto the outer circumferential surface of the advancing tubular stock a circumferentially complete jacket of cellular synthetic plastic; forming means adjacent a second convolution downstream of said first convolution and arranged to receive the jacketed stocks from said extruding means for forming the peripheral surface

layer of the jacket into a continuous smooth skin; cooling means downwardly spaced along said path from said forming means and located adjacent a third convolution downstream of said second convolution for cooling the resulting jacketed tubular product; and takeup means for said jacketed tubular product downwardly spaced from said cooling means for receiving and taking up the cooled jacketed tubular product.

2. Apparatus as defined in claim 1, wherein said feed means and said takeup means comprise drums rotatable about respective upright axes of rotation.

3. Apparatus as defined in claim 2, wherein said axes are at least substantially coaxial.

4. Apparatus as defined in claim 2, each of said drums supporting a coil of tubular stock of predetermined outer diameter and wherein the diameter of said convolutions is at least substantially equal to said predetermined outer diameter of at least one of said coils.

5. Apparatus as defined in claim 2, wherein said advancing means comprises an upper and a lower advancing device; and

20 wherein said advancing devices are synchronously driven.

6. Apparatus as defined in claim 2, said extruding means comprising an extruding die through which said tubular stock advances and wherein it receives said jacket; and further comprising liquid-support means downstream of said extruding die

25 at least in the region of said cooling means for supporting the jacketed tubular product advancing in said path.

7. Apparatus as defined in claim 6, said forming means being liquid operated and comprising a plurality of forming members having respective free edges which define with one

30 another a passage through which the jacketed tubular stock is compelled to pass in contact with said free edges.

8. Apparatus as defined in claim 7, wherein said forming members are adjustable with reference to one another.

9. Apparatus as defined in claim 2, said extruding means comprising an extruding die defining a passage, a hollow mandrel in said passage and defining therewith an annular extrusion gap coaxial with said passage, said mandrel having an inlet portion, an outlet portion and an intermediate portion; wherein said hollow mandrel has an inner diameter more than

40 twice the outer diameter of said tubular stock; and further comprising replaceable guide means in the region of said inlet and intermediate portions for guiding the tubular stock advancing in a helical convolution through said mandrel.

10. Apparatus as defined in claim 9, said guide means and

45 said outlet portion having openings for said tubular stock which extend tangentially to the curvature of said tubular stock.

11. Apparatus as defined in claim 9, said mandrel comprising two axially adjacent sections, and wherein said guide means comprises an annular guide member located between

50 said sections.

12. Apparatus as defined in claim 5; further comprising cutter means lower of said downstream advancing device and arranged for movement in said path and at the speed of said

55 jacketed tubular product.

13. Apparatus as defined in claim 12; and control means for intermittently controlling said cutter means.

14. Apparatus as defined in claim 13, said control means comprising feeler means and signal-generating means operated by said feeler means and operative for controlling said cutter means, said feeler means and impulse-generating means being arranged upstream of said lower advancing device.
